UNITED STATES PATENT OFFICE.

DAVID J. SCOTT, OF PLAINFIELD, NEW JERSEY, ASSIGNOR TO ISABELLA SCOTT AND DAVID J. SCOTT EXECUTORS OF THE ESTATE OF WALTER SCOTT, DECEASED, DOING BUSINESS AS WALTER SCOTT & COMPANY, OF PLAINFIELD, NEW JERSEY.

WEB-TENSION MECHANISM.

Application filed July 30, 1925. Serial No. 46,939.

This invention relates to web tension mechanism for rolls of paper used in printing or other machines.

It is customary in the art, at the present time, when a feeding web becomes slack to increase the braking action on the web roll and, conversely, when the web becomes taut to decrease the braking action on the web roll. Such devices are shown in the Letters Patent to Scott No. 558,426 of April 14, 1896, and in the Letters Patent to Jones No. 1,395,830 of Nov. 1, 1921.

So far as my knowledge goes, this braking action has always heretofore been applied to a roll mounted on a spindle that extends through the core of the roll; and, as these spindles are of considerable weight and length, it is an awkward and burdensome task to manipulate the spindles and rolls. One object of my invention is to provide braking means that will be associated with chucks; that is to say, short shafts having engaging means at the ends that enter the hollow cores of the rolls for a short distance only from each end of the roll.

With this and other objects in view, the invention consists in the hereinafter described arrangement of parts, combination of elements and features of construction, several preferred embodiments of which are shown in the accompanying drawings in which:

Fig. 1 is a vertical sectional view in the plane of line 1—1 of Fig. 2 of a device embodying one form of the invention:

Fig. 2 is an end view, partly in section and broken away, of the parts shown in Fig. 1, looking in the direction of arrow 2 of Fig. 1:

Fig. 3 is a side elevation of the actuator for the brake mechanism and adjacent elements:

Fig. 4 is an end elevation of the parts shown in Fig. 3 looking in the direction of arrow 4 of Fig. 3:

Fig. 5 is a fragmentary side elevation of one of the adjustable supporting members:

Fig. 6 is a view, partly in section, looking in the direction of arrow 6 of Fig. 5:

Fig. 7 is a detail view of one of the adjustable chucks and its supporting means:

Fig. 8 is a view similar to Fig. 1, being a section taken in the plane of line 8—8, of Fig. 9, showing a modified form of the invention:

Fig. 9 is a view looking in the direction of arrow 9 of Fig. 8:

Figs. 10, 11 and 12 are views of a portion of Fig. 9 with the parts in different positions when different widths of webs are used.

The invention is here shown clothed in the form it could take if embodied in a device similar to that shown in Letters Patent No. 1,124,673 of January 12, 1915, where a plurality of web rolls are mounted on a rotatable carrier so that when one roll is about to become exhausted, another roll may be moved into position whereby the paper supply may be replenished without necessarily stopping the machine but I wish it distinctly understood that this is but one of many forms that the invention might assume and that, so far as certain claims are concerned, the invention may be applied equally as well to a construction having but a single web roll.

1 indicates a printing, or other web-pulling, machine of any suitable construction having a bed-plate 2. 9, 10 and 11 indicate a plurality of web rolls that are, in the present embodiment, successively brought into feeding position with respect to the printing machine being here carried by rotatable supporting means consisting of a shaft 4 mounted in pedestals 3 and two spiders or supporting members 5 and 6, each of which spiders has three arms there being provision at the end of each arm for holding a chuck 8; that is to say, the two supporting members carry a plurality of sets of opposed chucks, one chuck of each set being on one, and the other on the other, of the supporting members, said chucks being adapted to project into and engage the hollow core 7 of a web roll. Supporting members 5 and 6 are adjustable lengthwise of shaft 4 toward and away from each other but on account of a key connection are rotatable with the shaft in any adjustable position. The roll 9 is shown in feeding position and the web 14, being the feeding web passing to the printing machine, is shown threaded through the parts. Shaft 4 carries a worm wheel 41 driven by worm 42 that may be turned by hand, or a motor, to bring successive web rolls into feeding position; and

it will be understood that if paste be applied to substitute or replenishing roll 10 and then, while the press is being run at slow

speed, the supporting means be rotated clockwise (in Fig. 1), roll 10 (being rotated slowly by hand) will come in contact with web 14 and 10 and 14 may then be pasted together. As soon as the two webs are joined, the web from roll 9 may be broken and roll 10 be moved into the position previously occupied by roll 9 and the exhausted core from roll 9 may be taken out and a fresh roll put in while in the position occupied by roll 11.

Suitable controlling mechanism, governed by the tension of the feeding web, and suitable brake mechanism for the web rolls are provided. Preferably, the construction is such that the brake mechanism relating solely to the roll in feeding position is affected by the controlling means, and also, preferably, the parts are so arranged that the movement of a new roll into feeding position will not merely bring the parts into such relation that the controlling mechanism and the brake mechanism may coact when coupled up, but the parts become automatically coupled or related so that no additional work, such as latching two parts together, is necessary. Preferably, the controlling mechanism, mounted independently of the supporting means for the web rolls, consists of a controlling member and associated elements, and an actuating member centrally disposed with respect to the web rolls.

The brake mechanism as here constructed is as follows: One or both of the chucks of each set carries a brake wheel 12 preferably V-shape against which are clamped the friction straps 13, with the usual adjustment for compressing the straps around the brake pulley to produce more or less braking effect. The tension straps 13, in addition to the usual hand screw adjustment, are mounted in such manner that the ends of the straps opposite the hand wheel adjustment are also movable to increase or decrease the wrap of the brake shoes by means of toggle 37 with the usual toggle connections. This toggle 37 has a brake rod 38 sliding through a bracket 39 and ending in an adjusting screw 40 which is in position to be acted on by cam 36 on sliding collar 35.

The controlling mechanism is here constructed as follows:

Cam 36 and sliding collar 35 constitute an actuating member centrally disposed with respect to the web rolls. The sliding collar is carried loosely on shaft 4, is adjustable lengthwise thereof, and is prevented from rotating by means of pin 43 extending into pedestal 3. Cam 36 is so shaped as to be active with respect to the brake rod of the web roll in feeding position.

Side register of the web can be obtained in the usual manner, either by shifting one of the pedestals 3 sidewise and with it the

shaft 4 and all that it carries, or shaft 4 may be mounted to slide back and forth to side register the webs; or, if preferred, each web can be side registered individually by moving the paper-roll spindle sidewise, such as is usually done on floor fed newspaper presses and in common practice in the art. Web 14 runs to spring roller 15 which is of the ordinary construction and provides some yield to the variations in the winding of the various rolls of paper. From this roller, the web passes underneath the automatic tension-adjusting roll 16 and from there on to press roller 17 and thence into the press. Tension-adjusting roller 16 is carried by arms 18 on shaft 19 which is pivoted in the frame or bracket 20. On shaft 19 there is an extension rod 22 and balance weight 23 which balance weight is adjustable by sliding closer to and farther from the shaft 19 and this counter-balances the weight of the roller 16 and arms 18. Carried also by shaft 19 is the lever 24 connecting with dash pot 25 which may be an air or oil checking device to steady the travel of the web-tension roller 16 and to prevent violent and continuous vibration of the roller. There is also carried on shaft 19, adjusting lever 26 carrying a roll 27 that operates a crank lever 28. This crank lever is pivoted to frame 20 at point 29. The spring 30 is arranged to pull up one end of crank lever 28, while to the other end there is pivoted connecting rod 31 having a piston 43 sliding in cylinder 44 containing oil or other fluid; and from this cylinder extends a duct 45 that connects with a cylinder 46 in which latter is seated a piston 47 subjected to the pressure of a spring 48 on one side and to the pressure of fluid from duct 45 on its other side. Piston 47 has a rod 49 suitably connected to bell crank 32 which is forked at its lower end and terminates in shoes 33 operating in groove 34 of sliding collar 35. It will be understood that in case it is desired to apply braking action on both ends of the roll, there may be another duct 45^a leading to the other side of the machine and to a similar arrangement and fluid actuated means and slidable collar. Inasmuch as all the chucks are constructed alike, a description of one will suffice. Chuck 8 is carried by a short shaft 50 that extends through an opening 50^a in an arm of a supporting member. This supporting member is also provided with a bracket 51 into which the short shaft 50 extends. Mounted in this bracket is a threaded member 52 that engages corresponding internal threads in shaft 50 so that by rotation of handwheel 53 shaft 50 may be moved back and forth to bring the chuck into or out of engagement with the core of the web roll. Brake wheel 12 is mounted on bushing 54 and there is a splined connection 55 between said bushing and

130

shaft 50 so that irrespective of the adjustment of shaft 50, brake wheel 12 will retain its position with relation to straps 13 and the braking relation between the chuck and the brake mechanism will be retained. It will be understood that if the chuck is provided with a braking mechanism as described and suitable connections such as the 5 slidable collar 35 and cam 36 are provided at each side of the machine, the braking action 10 may be applied to both ends of the web roll in response to variations in the tension of the web from the feeding roll. Instead of using a fluid pressure system, the form 15 of the invention shown in Figs. 8 and 9 may be employed. As here indicated, arm 28 is attached to a transversely extending rod 55 from which extends at opposite ends thereof connections 56 attached to bell crank 20 57 which latter, in turn, is connected with bell crank 32 by means of arm 58.

In Figs. 10, 11 and 12 are shown different ways of adjusting the device when it is desired to use a web roll of less width than standard. For instance, in printing machines it is customary to use a four-page wide web but it sometimes happens that it is desired to use only a two-page wide web, or a three-page wide web, or a web of other 25 smaller dimension. When it is desired to use a web of such smaller dimension, operating conditions may require that this web be run at one side of a machine, or at the other side, or in the middle, or at some other point. 30 In case it is desired to use a two-page wide web centrally of the machine, then the arrangement might be as shown in Fig. 10 where supporting members 5 and 6 are shown as having been adjusted toward each 35 other to enable the chucks to be brought properly into engagement with the web rolls; and, in order to transmit the motion from the connections controlled by the tension of the web, member 35 may be retained in its position and another member 59 with a cam 60 similar to cam 36 may be connected with member 35 or with the bell crank operating that member by suitable means, such as rod 61, so that member 59 40 and cam 60 will receive exactly the same motion as that imparted to member 35. In case it is desired to use a two-page wide web at one side of the machine, then the arrangement in Fig. 11 may be resorted to. In this 45 case, member 35 and cam 36 at one side of the machine are retained in their original position, as shown in Figs. 2 and 9; but, on the other side of the machine an auxiliary member 59 and auxiliary cam 60 may be 50 employed and a long connecting member 62 is used to transmit the motion. In case a three-page wide web is used at one side of the machine, then the arrangement shown in

Fig. 12 may be employed and this arrangement is substantially the same as that shown 65 in Fig. 11 except that a shorter connecting member 63 is used at one side of the machine.

While the particular means for transmitting motion from the web tension roller to the brake mechanism are shown in Figs. 10, 70 11 and 12 as being mechanical, it will of course be understood that the form of the invention shown in Figs. 1 and 2 may just as well be employed and the auxiliary connections and cams used with the same effect. 75

It is important that braking pressure be applied substantially equally at opposite ends of the roll. In the form of the invention shown in Figs. 1 and 2 it will be seen that the fluid pressure sends equal impulses 80 in both directions through ducts 45 and 45^a while in Figs. 8 and 9 equalizing bar 55 serves to transmit an equal movement to both of the connections 56.

I claim:

1. Tension device for web rolls including: 85 means for bringing web rolls, having hollow cores, one at a time into feeding position, a plurality of sets of chucks carried by said means to enter the hollow cores of the web 90 rolls, controlling mechanism governed by the tension of the web from the roll in feeding position, and a plurality of brake mechanisms one for a chuck of each roll movable with said means to co-act with said controlling mechanism as each roll comes into feeding 95 position.

2. Tension device for web rolls including: 100 means for bringing web rolls, having hollow cores, one at a time into feeding position, a plurality of sets of chucks carried by said means to enter the hollow cores of the web 105 rolls, controlling mechanism governed by the tension of the web from the roll in feeding position, and a plurality of brake mechanisms one for the chucks of each roll movable with said means to co-act with said controlling mechanism as each roll comes into feeding position.

3. Tension device for web rolls including: 110 means for bringing web rolls, having hollow cores, one at a time into feeding position, a plurality of sets of chucks carried by said means to enter the hollow cores of the web 115 rolls, controlling mechanism governed by the tension of the web from the roll in feeding position, and a plurality of brake mechanisms at each end of the rolls one for each chuck of each roll movable with said means to coact with said controlling mechanism as 120 each roll comes into feeding position.

Signed at Plainfield, in the county of Union and State of New Jersey, this 24th day of July, 1925.

DAVID J. SCOTT.
